[57] **ABSTRACT**
A control system and method for acquiring and automatically maintaining a register condition for successive repeat lengths of a moving web relative to a cut-off apparatus or the like in a web operating apparatus of the type which includes an adjusting means for adjusting the web. The system operates in manual and automatic mode, and while in the manual mode an image profile of the web is digitized, stored and processed to locate at least one suitable control mark. After the register condition is obtained and at least one control mark identified during the manual mode, the system can be switched to automatic mode to automatically maintain the registration condition using at least one control mark to detect deviation from the register of the web.

7-7-2 - 1 -7-7-2 - 2 -## METHOD AND APPARATUS FOR CONTROLLING WEB HANDLING MACHINERY

This invention relates generally to registration control and more particularly relates to a microprocessor based system and method for acquiring and maintaining a register condition in a web operating apparatus of the type which has a work applying means on the web at successive repeat lengths during movement thereof and which has a web adjusting means for advancing or retarding the position of the repeat lengths relative to the work applying means.

Register control systems have been used in the prior art for many years for the purpose of automatically presenting a web, such as paper in a printing press or the like, to a work applying means which may comprise a pair of cutting rolls that cut the paper at the proper location. Once the apparatus has been set up by the operator to cut the web at the proper location (i.e. the register condition), which occurs at each of successive repeat lengths of the web, the control system usually varies an upstream adjusting means which is usually in the form of a compensating roller which can be moved in a manner whereby the web location where the cut is to occur can be advanced or retarded so that the register condition can be maintained. These systems generally employ a scanner which detects one or more dark lines or other indicia on the web which occurs one or more times during each repeat length or signature, as well as an encoding generator which is operably connected to one of the cutting rolls of the work applying means so that it generates tach pulses for each revolution of the counter (often referred to as "once around" tach pulses). The relative occurrence of the tach pulse is then compared with the occurrence of the mark signal that is derived from the scanner to determine if the position of the web as it is presented to the cutter has moved relative to its register or proper position.

Many prior art systems employ an encoder to produce a "once around" pulse which after the register condition has been acquired during set up, must be adjusted to occur at the proper location for comparison with the mark signal that is produced by the scanner detecting the mark from the web. The encoders that have been utilized in many prior art systems have employed various techniques to properly position the encoder so that the one or more pulses occur at the proper time and have employed structural adjustment techniques to properly position the components which detect the pulses in the encoder. For example, a magnet which results in the generation of the "once around" tach signal for each revolution of the encoder shaft has been physically repositioned to provide the signal at the proper rotational position. Other systems have required movement of light sources and photo receivers therein, as well as rotating the commutator thereof. Still other devices have employed fiber optic cables to fixed sources and receivers with the fiber optic cables being capable of being repositioned. Virtually all of these techniques are intended to generate a "once around" tach pulse, i.e. one pulse for each revolution of the encoder, wherein the pulse occurs at the same time as the mark signal is generated by the scanner so that when the encoder is set up there is no difference between the occurrence of the mark signal and the tach pulse. Any subsequent advancement or retardation of the web during operation will result in a difference between the

occurrence of these two signals which can be used to make a correction. Systems have been used which generate a few thousand pulses per revolution in addition to the "once around" pulse, but the greater number of pulses are used only to determine the magnitude of the error between the occurrence of the mark signal and the "once around" tach signal.

Most of these prior art systems employ a complex encoder reference generator which must be manipulated during the setting up of the apparatus. An advanced prior art system avoids the use of a "once around" tach signal and employs a conventional encoding reference generator which merely produces a predetermined number of pulses together with an indication of the direction of rotation of the encoder shaft.

However, all such prior art systems are primarily suited for systems in which a special mark is placed on the web. This is unfortunately wasteful of valuable material. Further, these prior art systems require manual adjustment of scanner sensitivity to compensate for changes in the scanner light source, dirt on the scanner, etc. The present invention presents a radical departure from the prior art by analyzing the existing signature of the web to automatically locate a mark and generate a register condition as well as automatically adjust the effective sensitivity of the scanner.

Accordingly, it is an object of the present invention to provide an improved register control system and method which presents a significant improvement over the prior art register control systems and which does not experience many of the problems of those systems.

It is another object of the invention to provide an improved system that is operable in manual and automatic modes, wherein a mark is automatically chosen and the register condition is set up while in a manual mode and upon switching to an automatic mode the register condition is automatically maintained.

Another object of the present invention is to provide an improved register control system and method which digitizes and stores an entire signature and uses a microprocessor to process the signature to determine a suitable mark for use in maintaining a register condition.

It is still another object of the present invention to provide an improved register control system and method that automatically adjusts scanner sensitivity.

Briefly, according to one embodiment of the invention, a method is provided for acquiring and maintaining a register condition for successive repeat lengths of a web that is acted on by work applying means of a web operating apparatus which also has adjusting means for adjusting the position of said repeat length relative to said work applying means. The method comprises scanning the web and digitizing a plurality of successive data points to form a digital map of a cross-section of the web image, and then storing the digitized data points. The stored data points are processed to locate contrast changes which meet predetermined minimum conditions and the located contrast changes are reduced to a predetermined number of control marks and stored in a memory. The location of at least one control mark is then detected for each successive repeat length and the difference between the initial location of at least one control mark and the detected location of the respective control mark is measured and an error signal is generated in response to said difference for each successive repeat length. The adjusting means is then driven to advance or retard the position of said repeat lengths in response to the error signal.

BRIEF DESCRIPTION OF THE DRAWINGS

The features of the present invention which are believed to be novel are set forth below with particularity in the appended claims. The invention, together with further objects and advantages thereof, may be understood by reference to the following description taken in conjunction with the accompanying drawings.

FIG. 1 is a diagrammatic illustration of a register control system shown in conjunction with a web operating apparatus and embodying the present invention.

FIG. 2 is a generalized block diagram of the electronic circuitry of a specific embodiment of a control system according to the present invention.

FIG. 3 is a detail block diagram of the electronic circuitry of a specific embodiment of a control system according to the present invention.

FIG. 4 is an electrical schematic diagram of specific circuitry that can be used to implement a portion of the operation of the block diagrams of FIGS. 2 and 3.

FIG. 5 is an electrical schematic diagram of specific circuitry that can be used to implement a portion of the operation of the block diagrams of FIGS. 2 and 3.

FIG. 6 is an electrical schematic diagram of specific circuitry that can be used to implement a portion of the operation of the block diagram of FIGS. 2 and 3.

DETAILED DESCRIPTION OF THE PREFERRED EMBODIMENT

Referring to FIG. 1 there is shown a diagrammatic illustration of a control system embodying the present invention together with a portion of a web operating apparatus 10 which is specifically illustrated to have a web cutter 11 and position adjusting mechanism 20. The control system of the invention provides compensation for minor changes in the web operating apparatus registration, primarily changes due to circumferential stretch of the web. While the control system described herein is in conjunction with a web operating apparatus that utilizes these components, it should be understood that the control system described herein is useful in other applications.

The web operating apparatus 10 shown in FIG. 1 has a cutter mechanism 11, which includes an upper roller 12 having a knife 14 and a lower roller 16 having an anvil 18 which cooperates with the knife 14 to make a transverse cut of the web 13 for each rotation of the rollers 12 and 16. The rollers 12 and 16 are driven in synchronism and are accordingly sized so that the transverse cuts are made on the web 13 at each repeat length or signature as desired.

The web operating apparatus 10 also includes web adjusting equipment 20, which includes rollers 22 and 24 to guide the web 13, the web 13 passing over the third roller 26 that can be vertically adjusted to either advance or retard the position of the web 13 that is presented to the cutter apparatus 10. The compensating roller 26 has its shaft journaled at opposite ends in member 28 which has a threaded aperture that is cooperatively connected to a threaded bolt 30 which can be rotated in opposite directions to raise or lower the member 28 and therefore the roller 26. The shaft 30 has a pulley 32 which is linked to a pulley 34 by belt 36, although it can be a chain or the like, with the pulley 34 being attached to the drive shaft 38 of a correction motor 40, as shown.

The system of the present invention is shown to include a control panel 42 having an off-on switch 44, a

manual-automatic switch 43, test switch 45, retard and advance push buttons 46 and 48, a correction motor speed adjustment knob 50, a digital display 52, together with a mark pulse indicator 54, an automatic mode indicator 56, a manual mode indicator 58 and advance and retard indicators 60 and 62, respectively. A set of four sixteen-position selection switches (not shown) are also provided to permit presetting constants that are dependent upon the particular web operating apparatus. 5 A scanner 66 is mounted just above the web 13 adjacent to the roller 24 and is mounted by a structure indicated generally at 68 so that it can be vertically adjusted relative to the web 13 for the purpose of optimizing the signals that are detected by it. The signals that are generated by the scanner are sent to the control system circuitry (see FIGS. 2 and 3) housed behind the control panel 42 via conductors 70, and similarly, cable 72 extends to the correction motor 40 for operating the motor to advance or retard the web 13. The system 10 includes an encoding generator 74 (hereinafter referred to as the shaft encoder or merely the encoder) that has an encoder shaft 76 with a pulley 78 that is operatively connected to the lower roller 16 via a belt 80 that is carried by a pulley 82 on the shaft 84 of the roller 16. 15 The size of the pulleys 84 and 78 are determined such that a one to one ratio of rotation is established, i.e., for each rotation of the roller 16, there will be a single rotation of the shaft 76 of the encoder 74. The output signals that are generated by the encoder 74 are sent to 20 the control system circuitry via lines 86 and power for the system is supplied to the control circuitry by lines 88. It should be noted that since the encoder shaft is essentially measuring very precise positions, the connection between the shafts 74 and 84 should be optimized and it is often preferred that they be directly coupled together.

In operating the system shown in the drawings, an operator will set the switch 43 in the manual position which enables him to actuate either the advance or retard switches 46 and 48 which will cause the correction motor 40 to operate and either advance or retard the position of the web 13 that is presented to the cutter 14 and anvil 18 so as to produce the cut at the desired location. After the operator has made the proper adjustment to obtain the cut at the desired location with respect to the signature or successive repeat lengths of the web, the system electronics scans the signature, digitizing and storing 3600 data points thereby creating a digital map of a cross section of the entire signature 25 image for the repeat length of the web 13. In an alternative approach, only a substantial portion of repeat length is scanned, where a substantial portion is a portion sufficient to ensure identification of a suitable control mark. The system then processes this digital information to automatically adjust the scanner sensitivity and analyzes the digital data to determine a suitable control mark from the signature to be used for automatic control of the web operating apparatus 10. Once at least one control mark has been determined, the operator can switch the switch 43 to the automatic setting and it will automatically maintain the register condition during operation provided the web 13 does not physically slip a large distance relative to the rollers 12 and 16. In the event of such large slippage occurring, the system also offers a manual intervention capability of incrementally advancing or retarding the web 13 during 30 automatic operation. This can be done by merely depressing the advance or retard push buttons 46 and 48, 35 40 45 50 55 60 65

with the amount of movement being determined by the duration of the pressing of the appropriate push button by the operator. When the system is being set up in manual mode, the indicator light 48 provides an indication that the scanner is sensing marks and determining an appropriate control mark or other indicia on the web. The marks that are detected by the scanner and stored must be processed and analyzed to determine whether they satisfy certain requirements regarding isolation from one another, slope of contrast changes, etc. After the operator has determined that one or more valid control marks have been determined, he can then switch to automatic operation and the system will thereafter operate automatically to maintain the register condition.

When the system is operating in the automatic mode a digital display 52 will provide an indication as to the amount of error that is present. It should be noted that when the web is moving very rapidly and has shifted so that the signature has moved relative to the cutter apparatus 10, several cuts may occur before the adjusting mechanism 20 can regain the register condition and the digital display 52 indicates this progress and whether an error is present. Prior to display of the error, the error signal is normalized relative to the repeat length of the web operating apparatus such that each count of the displayed value represents a fixed length of the web.

For a more detailed description of the operation of the system, reference is made to FIGS. 2 and 3. FIG. 2 is a general block diagram illustrating the electronic circuitry that is incorporated in the system to perform the various system functions in accordance with the invention. The scanner 66 detects a reflected light level through the use of a light source which is directed toward the web 13 and a light sensitive photo-diode which detects the reflected light from the web 13 and provides a signal to an analog to digital (A/D) converter 92 and to a processor 100, as shown. The scanner 66 effectively measures a change in light level, for example, a change from a light level to a dark level which would occur due to presence of a dark line or other indicia that is printed on the web. The A/D converter 92 samples and digitizes (e.g., eight bits per sample in the preferred embodiment) the signal from the scanner at a rate of 3600 samples per repeat length and couples the resulting digital data to the processor 100. The processor 100 is the control logic for the system comprised primarily of a programmed microprocessor (e.g., an Intel 8031), random access memory (e.g., 5511's) and related logic circuitry (for detail see FIGS. 3-6). The processor 100 stores the digital data from the A/D converter 92 in random access memory (RAM) and processes the data to locate suitable marks and determine the effective scanner sensitivity. A computer program listing of a program for use in the embodiment illustrated in FIGS. 3-6 is attached hereto and is hereby incorporated as part of this specification.

An encoder 74 (e.g., 700 series shaft encoder manufactured by Disc Instruments, Inc., Costa Mesa, Calif.) produces an output comprising two 1800 cycle square waves per revolution of its shaft, where its shaft is connected to the shaft 84 of the roller 16 as shown in FIG. 1. The two square waves produced are 90 degrees out of phase with each other such that one wave leads the other by 90 degrees during clockwise rotation, and the opposite phase relationship exists for counter clockwise rotation. Thus the output of encoder 74 contains position and direction information. These output signals are

applied, as shown, to a multiplier clock generator 94 which produces a set of clock signals at a rate of 3600 pulses per repeat length including direction dependent signals which are coupled, as shown, to the processor 100. These clock signals are utilized by the processor 100 to accumulate a count of pulses to maintain a precise indication of shaft position, i.e., a position count. The processor 100 also utilizes the clock signals for other purposes including the determination of the primary direction of rotation automatically, the instantaneous direction of rotation, and information used for incrementing and decrementing the position count to keep track of position changes due to rotation in either direction. Also coupled to the processor 100 are output display devices 96 (e.g., lights, seven segments displays, etc.) and input controls 97 (e.g., push button switches, selection switches) such as are shown in FIG. 1 with reference to the control panel 42. In addition, output control signals are coupled from the processor 100 to the correction motor drive circuitry 98 to provide control of the correction motor 40, as shown.

In operation, the system 10 is started by an operator who powers up the system and places it in a manual mode by activating the manual switch 43. In the manual mode the operator can advance or retard the position of the web by activating the advance 48 or retard 46 switches to produce the cut at the desired location. After the proper adjustment has been made to obtain the cut at the desired location, the processor 100 begins the scan of the web signature, storing 3600 samples digitized by the A/D converter 92 from the scanner 66 and clocked in by a clock signal produced by the multiplier clock generator 94. These data samples are stored in random access memory (RAM) within the processor 100 (see FIG. 3). Once a complete set of 3600 samples has been stored, providing a profile map of the signature image (i.e., a longitudinal profile of indicia located on the web surface), the processor 100 analyzes the data to identify indicia contrast changes (i.e., light level changes) suitable for use as control marks. To perform this analysis the processor 100 identifies local valleys (minimums) and peaks (maximums) of light intensity within the sampled profile and then calculates the slope of these contrast changes by calculating the difference between adjacent maximum and minimum values and dividing by the number of position counts between maximum and minimum values. In addition, a mid-point value is calculated to be used to establish a trip point. The address in memory of each located contrast change corresponds to the position count accumulated by the processor and thus corresponds to the location within the signature. In the illustrated embodiment, up to 16 contrast change regions are identified and stored if they have a certain minimum required slope which is determined by a programmable constant. The slope constant can be changed, as described hereinafter to provide for various image sizes. Once the sixteen suitable contrast change regions have been found, they are reduced to a predetermined number (four in the preferred embodiment) with the largest slope since a sharp transition permits a more detectable reproducible mark. The retained four regions are then subjected to a gate analysis.

The gate analysis determines which contrast change regions are at least a predetermined minimum distance from adjacent contrast changes so as to provide a predetermined time window located around the contrast region within which only the desired contrast change can be found. During gate analysis, the number of con-

trast change regions may be reduced to one or in the alternative to several contrast change regions. These remaining contrast change regions are to be used as control marks for automatically maintaining registration of the web. Assuming, as in the specific embodiment illustrated, the contrast regions are reduced to one control mark, the location of the mark is stored and the mid-point trip value is output through a digital to analog (D/A) converter to a comparator for comparison to the output of the scanner. This effectively provides adjustment of the sensitivity of the scanner system to compensate for variations in scanner light levels. A time window gate is then set up to activate the comparison only during the time window of predetermined length during which the chosen mark is expected. A test cycle is subsequently run to check the control mark to determine whether it is produced at the expected location. To locate the mark, the comparator is triggered by detection of a contrast change and if it occurs during the time window, the processor 100 captures the address (position count) of the detection and compares that address to the initial address of the stored control mark. The difference is used to generate an error signal. If the difference or error signal during the test cycle is less than a predetermined constant value, which is programmable to provide for different web operating apparatus deviation characteristics, then the control mark is accepted. If the control mark does not meet requirements during the test cycle, the entire process is repeated beginning with acquisition of a new sample profile.

During the manual mode while the system is digitizing and analyzing data and during the test cycle, the mark pulse light 54 flashes on and off slowly. After the test cycle has been completed and the control mark is accepted, the mark pulse light flashes in a blip fashion which indicates to the operator that the system can be switched to automatic. Once switched to automatic, the processor 100 operates as in the test mode to detect the difference between the occurrence of the control mark and its expected initial location as well as detecting whether the control mark occurs early or late, and generates an error signal as well as an advance on retard signal based upon the difference. This difference in location between the control mark and its initial stored location is normalized such that the units produced represent a consistent length of the web (e.g., six thousandths of an inch in the preferred embodiment) regardless of the impression size of the apparatus used and this normalized value is displayed on the display 96. The error signal is applied to the correction motor drive circuitry 98 to automatically maintain the registration condition of the web by selectively advancing or retarding the web position in response to the error signal. During automatic operation no correction is made unless a minimum error of a predetermined number of counts is detected, thus creating a desired error "dead zone", which is programmable to accommodate a variety of web operating systems.

One source of variation in the control mark location, which is tested during the test cycle, can be caused by lateral movement of the web. When the control mark is the result of an edge of a contrast change region wherein the edge is not perfectly perpendicular to the direction of travel of the web (i.e., the line of the contrast change angled or curved) a lateral movement of the web will result in relative movement of the control mark position even though the web registration condi-

tion has not changed. Thus, a test cycle or several test cycles can be run to determine whether the mark shifts too much while the web is moving. During the manual mode, the test cycle can continuously monitor the deviation from the expected position of the control mark over a succession of repeat lengths and if the error exceeds a predetermined acceptable limit, the mark is discarded. This provides a means of minimizing the probability of an unacceptable mark which will vary with lateral movement of the web.

In an alternative implementation of the illustrated embodiment another technique is used to further reduce the probability of an angled or curved mark. At the point during manual mode that the processor 100 has identified several (preferably four) potential control marks with the minimum isolation required, these marks and associated time windows are retained as control marks and the system can be put into the automatic mode. During automatic mode, the remaining control marks are used for maintaining registration and the error for each mark is continuously monitored. The control marks can then be slowly discarded until only a minimum number (preferably one) remain based upon the variation in error and the relationship between of the errors of each mark. This permits a highly reliable means of discriminating out the angled or curved marks.

Another feature of the system provides for the use of a preprinted pattern on the web, such as a pattern composed of two small parallel lines with predetermined spacing between them. Thus the processor 100, after accumulating the digitized profile, would search for two marks with the predetermined spacing and then use that mark as the control mark as described hereinbefore. If the preprinted mark is not found, the processor 100 then uses the above described method for locating a suitable control mark.

During automatic operation, the processor 100 can compensate for detected error by one of two alternative methods. In the first method the correction motor speed is adjusted by the operator and the processor 100 activates the motor to make the corrections proportional to the amount of detected error. This approach can lead in some circumstances to overshoot or undershoot (i.e., hunting) due to such factors as transportation delay. In an optional approach, the processor 100 activates the correction motor 40 based upon the rate of change of the error signal (i.e., a derivative) or some combination of the derivative and other factors such as transportation delay, type of paper, etc. In this manner the processor 100 can analyze the rate of change of the error signal and other factors to set the control loop gain.

A number of input controls 97 are coupled to the processor 100 to allow the operator to preset a number of the programmable constants utilized by the processor 100. A sixteen position switch allows an image size (i.e., impression size) of the printing press to be preset to permit use of different size printing presses with the system. This results in presetting those constants which are directly determined by the impression size. Another sixteen position switch allows presetting the time window size to be compatible with the maximum registration deviation of the press. A third and fourth sixteen position switch allows presetting printing speed and presetting the "dead zone" value.

Referring to FIG. 3 there is shown a detail block diagram of the system of FIG. 2. Detail schematic circuit diagrams of a specific embodiment corresponding to the block diagram of FIG. 3 are shown in FIGS. 4

through 6 with corresponding blocks shown enclosed within dash lines and labeled with corresponding reference numerals. As illustrated in FIG. 3, a microprocessor 110 coupled via a bus 111 to a program memory 114 containing program instructions for the microprocessor 110 form the central control logic of the processor 100. By reference to FIG. 4 it can be seen that this control logic is implemented using an Intel 8031 microprocessor and an Intel 2764 UV erasable, programmable read only memory (EPROM) which provides an 8K by 8 program memory. The bus 111 is coupled to the standard system bus 123 through latch/buffer circuitry 118. As shown in FIG. 4, the latch 118a is implemented using a 74LS373 latch as an address latch and the buffer 118b is implemented using a 74LS245 tri-state bus transceiver which provides isolation when the program memory 114 is being read by the microprocessor 110. In addition, the processor 110 is coupled to the system bus 123 via the address latch 122 utilizing a 74LS373 tri-state latch as shown in FIG. 4. Also shown in FIG. 4 is a chip select decoder 147 implemented using a 74LS138 decoder to generate chip select signals for selection of functions located on external circuit boards such as shown in FIGS. 5 and 6, as well as conventional power up circuitry 115 and read/write signal generating logic 117.

In FIG. 3 there is shown timer/counter and interrupt logic 150 together with a clock generating circuit 146 coupled to the system bus 123. This circuitry performs most of the counting/timing functions thereby freeing the microprocessor 110 for other tasks. The timer/counter 150 is composed as shown in FIG. 4 of an Intel 8253 programmable timer/counter 150a in conjunction with a dual 556 timer functioning as a dual clock, and as shown at 150b an Intel 8253 programmable timer/counter 151 in conjunction with a 74LS393 dual, 4 bit counter utilized to freeze the timer/counter 151. Each 8253 programmable timer/counter includes three 16 bit programmable timer/counter circuits (i.e., counter zero, one, and two) thus providing a total of six timer/counter functions. The timer/counter 151 (FIG. 4) provides a "once around" count using the counter zero, a pregate count using counter one, and a gate counter using counter two. The "once around" counter is set arbitrarily to zero at start up and is programmed to count the CKTC clock pulses to 3600 and then reset, thus providing a position count (i.e., location address) for a complete repeat length of the web, and producing a once around interrupt at reset. The CKTC and other encoder dependent clock signals are generated from the encoder signals by the multiplier clock generator 94 which is implemented as shown in FIG. 6.

The once around interrupt signal is coupled to the microprocessor 110 through the gates 153, 155 as shown, and indicates to the microprocessor 110 the end of a repeat length. The once around interrupt is also coupled to counter one of the timer/counter circuit 151, the counter two of the timer/counter circuit 150a, as shown in FIG. 4 and to the direct memory access (DMA) circuitry 142 shown in FIG. 5. The counter one of the timer/counter 151 is triggered by the once around interrupt to start a pregate count which determines the time interval from the generation of the once around interrupt to the beginning of the control mark time window. The output of the counter one triggers the counter two of timer/counter 151 to start the gate count, which determines the control mark time window. The counts used are programmable values and in

the preferred embodiment are determined by a set of switches 97 shown in FIGS. 3 and 6.

In the illustrated embodiment the control mark time window is centered when the system is switched to automatic by changing the phase of the once around counter to place the control mark near the center of the once around count. This separates in time the once around interrupt from the control mark. Once a control mark is detected by the comparator 126 (see FIGS. 3 and 5), the comparator generates a control mark interrupt (SCED) which is coupled to the microprocessor 110 via a counter 157 as shown in FIG. 4. The counter 157 also disables the timer/counter circuit 151 for a preselected number of encoder counts (i.e., four counts in the preferred embodiment) thus freezing the timer/counter 151 for a period of time sufficient to allow the counter to be read by the microprocessor 110 (i.e., determine the mark location). In response to the control mark interrupt, the microprocessor 110 subtracts the mark location from the stored initial mark address to obtain an error count. This value is normalized by the microprocessor 110 and displayed on the display 96 during the automatic mode, and is used to generate an error signal to control the correction motor 40.

The second timer/counter circuit 150a shown in FIG. 4 also comprises three timer/counters zero, one, and two which function primarily as I/O timers. The counter zero is utilized to control the correction motor (e.g., a synchronous motor) turn on time. The error count is loaded into the counter zero which then counts down with the motor on until zero is reached. The counter zero is clocked by pulses generated by one-half of the dual 556 timer 146 with the clock frequency controlled by an adjusting potentiometer 148, as shown in FIG. 4. Thus the potentiometer controls the motor speed. The counter one of the timer/counter circuit 150a functions as a watch dog timer in the automatic mode to reset the system if no mark signal is detected within a predetermined period (e.g., one and one-half repeat lengths in the preferred embodiment). The control mark interrupt resets the counter one of the timer/counter circuit 150a to a count equal to one and one-half times that for a complete repeat length (e.g., 4800) and the counter one is clocked by the multiplier clock signal CKT. If the counter one reaches zero, indicating that no control mark was detected, it resets the microprocessor 110. Finally, the counter two of timer/counter circuit 150a is used as a system interlock speed check counter so that the system is stopped if the speed of the apparatus drops below a preselected value. A clock signal of fixed frequency (one kilohertz in the preferred embodiment) is generated by the second half of the 556 timer 146 and is coupled to the counter two of the timer/counter circuit 150a which is configured as a retriggerable one shot with a preset count. The retriggerable one shot is triggered by the once around interrupt and counts down based on the fixed frequency clock. If the count reaches zero before the next once around interrupt resets the counter, indicating that the system is moving too slowly, a microprocessor interrupt is generated and coupled to the microprocessor 110, as shown in FIG. 4.

In addition to the external counters, there are two 16 bit counters (T1, T0) internal to the microprocessor 110 which are used as reverse count absorbers. The clock signals CKUC (which generates pulses only during clockwise rotation) and CKDC (which generates pulses only during counter clockwise rotation) are coupled to

these clock inputs from the clock multiplier generator 94 as can be seen by inspection of FIGS. 4 and 6. The counter (T1 or T0) which is receiving pulses at the time the system is switched to automatic is assumed to be the primary direction of the system apparatus and therefore the other counter is used to count any pulses which are applied, thereby acting as a reverse count by counting reverse clock pulses. This reverse count is used to rephase the clock count in the timer/counter 151 since the timer/counter 151 continues to count when the web is traveling the reverse direction. This reverse counter (i.e., T1 or T0) is then reset allowing it to continually monitor for reverse pulses.

During both manual and automatic operation the scanner 66 serves as a transducer detecting light levels reflected from the web and converting them to representative electrical signals (SCIN) which are coupled as shown in FIGS. 3 and 5, and the A/D converter 92 and the comparator 126. A commercially available scanner (e.g., a SICK #NT8) is used with a fixed aperture and comprises a light source which illuminates the web through a one way mirror and lens. This light is reflected off the web, back through the lens, and is reflected off the one way mirror to a main photo-diode for detection. Part of the light from the light source is reflected off a second mirror to a second photo-diode to monitor the light output of the source. This signal is used internal to the scanner to compensate the main photo diode output for variations in light source output. The compensated scanner signal (SCIN) is then amplified and coupled to the A/D converter 92 and the comparator 126.

The A/D converter 92 in the illustrated embodiment is a high speed flash converter (e.g., National Semiconductor ADC0820) which samples and digitizes the scanner signal. The A/D converter 92 is clocked by two multiplier clock generator 94 signals $\overline{CKS}$ (for read triggering) and CKC (for write triggering) as shown in FIG. 5. These signals are also coupled to the direct memory access (DMA) circuitry 142, as shown in FIGS. 3 and 5. The digitized samples from the A/D converter 92 are coupled to the data memory 138 composed of random access memory and to a buffer 134. The buffer 134 provides isolation to prevent access to the data RAM 138 by the microprocessor 110 while the A/D converter 92 is loading the data RAM 138. As illustrated in FIG. 5, the data RAM 138 is implemented utilizing 5516 static 2K by 8 random access memory and the buffer 134 is implemented using a 74LS245 tri-state buffer.

The DMA circuitry 142 is also coupled as shown in FIG. 3 to the data RAM 138 and is implemented as shown in FIG. 5 utilizing 374LS191 presetable synchronous counters, a 74LS157 decoder (i.e., multiplexer) and a 74LS74 dual, D-type flipflop. The synchronous counters in FIG. 5 function as address counters for loading the memory during direct A/D converter access. This is initiated by the microprocessor 110 with the starting address loaded by the microprocessor 110 at the start of the digitizing cycle. The counters are presetable and are therefore transparent to the microprocessor 110 when it needs to read or write the RAM directly. The decoder circuit functions as steering logic which triggers the A/D converter and the address counters during the digitizing cycle in re-

sponse to the microprocessor 110 and provides for selection of direct read-write RAM access by the microprocessor 110. The 74LS74 dual synchronous flipflop circuit provides synchronization of the address counters with the once around interrupt (INT) and generates a digitizing signal (DZG) coupled to the microprocessor 110.

Referring again to FIG. 3, a digital analog (D/A) converter 130 is shown coupled to the bus 123 to convert a digital trip point value calculated by the microprocessor 110 to an analog signal which is then applied to a comparator 126, as shown. The D/A converter 130 is implemented, as illustrated in FIG. 5, using a 558 latchable digital-to-analog converter and the comparator 126 is implemented using a conventional 311 operational amplifier. Also coupled to the comparator 126 is the scanner signal (SCIN) which is compared to the trip value. If it is greater than the trip value, indicating the detection of a control mark, an interrupt (SCED) is generated and coupled to the microprocessor 110.

Also coupled to the bus 123 are the display 96, switches and related interface circuitry 97, as shown in block diagram form in FIG. 3 and illustrated in greater detail in FIG. 6. Referring to FIG. 6, the interface circuitry is implemented primarily utilizing an 8255 programmable peripheral interface circuit which provides two ports to the bus from a set of switches (SW1, SW2, SW3, SW4) which allow the programming of system constants, and a third port that serves as an output port for light signals (MX, MAN, AUTO, TEST, AD1, AD2, RD1, RD2) and for external advance and retard signals to the correction motor (ADX, RDX). A set of MC14495 BCD to seven segment decoder/drivers are used to implement the interface to a two digit error display. A set of push buttons for advance (AD), retard (RD), test and auto interface to the bus through a 74LS173 tri-state latch. These inputs are also coupled, as shown, to a fused logic gate array 96a which functions as steering logic to allow manual control of the motor even when the microprocessor 110 malfunctions. This logic array also generates a "switch activated" signal ARA which allows the microprocessor 110 to monitor the use of the advance and retard switches for manual intervention.

Also shown in FIG. 6 is a detailed schematic of the multiplier clock generator 94 which is implemented using a 2630 optical isolator for isolation, a set of gates, and a fused logic gate array 94a. This circuit generates, from the two phase encoder signals (E1, and E2) a set of clock signals for various control and counting functions, as shown.

A specific embodiment of a novel method and apparatus for controlling web handling machinery has been described for the purposes of illustrating the manner in which the invention may be used and made. It should be understood that the implementation of other variations and modifications of the invention in its various aspects will be apparent to those skilled in the art and that the invention is not limited thereto by the specific embodiments described. It is therefore contemplated to cover by the present invention any and all modifications, variations or equivalents that fall with the true spirit and scope of the basic underlying principles disclosed and claimed herein.

REGISTER BANK(S) USED: 0

ASSEMBLY COMPLETE, NO ERRORS FOUND

What is claimed is:

1. A method of acquiring and maintaining a register condition for successive repeat lengths of a web that is acted on by work applying means of a web operating apparatus which also has adjusting means for adjusting the position of said repeat lengths relative to said work applying means, comprising the steps of:

(a) scanning the web to produce a scanner output and digitizing the output into a plurality of successive data samples;

(b) storing the digitized data samples to form a digital map of a cross-section of the web image;

(c) processing the stored digitized data samples to determine the location of contrast changes which conform to predetermined conditions by identifying regions of contrast change and determining slope values between maximum and minimum light levels in the contrast change region and storing the location of at least one contrast change region in response to the slope value meeting predetermined conditions;

(d) determining at least one control mark from the located contrast changes and storing the location of at least one control mark;

(e) detecting the location of at least one control mark for each successive repeat length;

(f) measuring the difference between the stored location of at least one of said control marks and the detected location of the respective control mark and generating an error signal in response to said difference;

(g) driving the adjusting means to selectively advance or retard the position of the repeat lengths in response to the error signal.

2. The method of claim 1 wherein said error signal indicates the magnitude of the measured difference and whether the control mark was detected before or after the stored location.

3. The method of claim 1 further comprising the step of generating at least one time window of predetermined duration around each control mark stored location and disregarding any control marks that are outside the time windows.

4. The method of claim 2 wherein the step of driving said adjusting means further comprises energizing a synchronous motor in a first direction when said control mark is advanced and in a second direction when said control mark is retarded, the energization occurring for a time that varies in proportion to the magnitude of the error signal.

5. The method of claim 1 wherein the step of determining comprises identifying contrast change regions adjacent to the located and stored contrast change regions and discarding any located and stored regions having adjacent regions within a predetermined time window while retaining as control marks at least one of those located and stored regions remaining.

6. The method of claim 5 wherein the location and duration of said time window is programmable.

7. The method of claim 5 wherein a comparator threshold value is computed for each control mark retained responsive to the minimum and maximum light level of the contrast change region of each respective control mark.

8. The method of claim 7 wherein the step of determining further comprises comparing scanner output for at least one additional repeat length to the comparator threshold during the corresponding time window for each control mark to detect the location of the control mark and discarding those control marks which differ from their stored location in excess of a predetermined amount.

9. The method of claim 8 wherein the method is repeated starting with the step of storing and digitizing in response to all control marks being discarded.

10. The method of claim 5 wherein the step of determining further comprises monitoring the difference over successive repeat lengths between the detected location of retained control marks and the respective stored initial locations of each control mark, and discarding control marks in response to the difference.

11. The method of claim 2 wherein the step of driving the adjusting means further comprises inhibiting the driving of the adjusting means in response to said measured difference being less than a predetermined minimum.

12. The method of claim 2, wherein the step of driving the adjusting means further comprises energizing a motor in a first direction when said control mark is advanced and in a second direction when said control mark is retarded, the energization occurring for a time and at a speed that varies in response to a derivative of the error signal.

13. The method of claim 2 wherein the step of measuring further comprises the step of normalizing the measured difference in location and displaying the normalized difference.

14. A control system, for acquiring and automatically maintaining a register condition for successive repeat lengths of a web that is acted upon by work applying means of a web operating apparatus which also has adjusting means for adjusting the position of said repeat lengths relative to said work applying means, said control system comprising:

(a) means for scanning the web to produce a scanner output and for digitizing the output into a plurality of successive data samples;

(b) means for storing the digitized data samples to form a digital profile map of a longitudinal cross-section of at least a substantial portion of the repeat length of the web;

(c) means for processing the stored digitized data samples to determine the location of contrast changes which conform to predetermined conditions;

(d) means for determining at least one region of contrast change and control mark from the located contrast changes and storing a location at least one control mark and means for computing a comparator threshold value for at least one control mark responsive to minimum and maximum measured light levels within the associated contrast change region;

(e) means for detecting the location of at least one control mark for each successive repeat length responsive to the relationship between the comparator threshold value and the digitized data samples;

(f) means for measuring the difference between the stored location of at least one control mark and the detected location of the repeated control mark and for generating an error signal in response to said difference for each repeat length;

(g) means for driving the adjusting means to selectively advance or retard the position of the repeat lengths in response to the error signal.

15. The control system of claim 14 where the means for measuring comprises means for generating an error signal which indicate the magnitude of the measured difference and whether the control mark was detected before or after the stored location.

16. The control system of claim 14 further comprising first switching means for switching said control system between a manual and an automatic mode of operation, and second switching means, operatively connected to said adjusting means and effective to energize said adjusting means to advance or retard the web location to acquire a register condition while in manual mode.

17. The control system of claim 14 further comprising means for generating of time window of predetermined duration around each control mark initial location and for inhibiting detection of any control mark not within its respective time window.

18. The control system of claim 15 wherein the means for driving the adjusting means further comprises means for energizing a motor in a first direction when said control mark is advanced and in a second direction when said control mark is retarded, the energization occurring for a time that varies in proportion to the magnitude of the error signal.

19. The control system of claim 15 wherein the means for driving the adjusting means further comprise means for energizing a motor in a first direction when said control mark is advanced and in a second direction when said control mark is retarded, the energization occurring for a time that varies in response to a derivative function of the error signal.

20. The control system of claim 14 wherein the means for processing comprises means for determining slope values between maximum and minimum measured light levels in the contrast change region, and means for storing the location of at least one contrast change region in response to the slope value exceeding predetermined conditions.

21. The control system of claim 20 wherein the means for determining comprises means for identifying contrast change regions adjacent to the located and stored contrast change regions and for discarding any located and stored regions having adjacent regions within a predetermined time window while retaining as control marks at least one of the located and stored contrast change regions remaining.

22. The control system of claim 21 wherein the time window is programmable.

23. The control system of claim 14 wherein the means for determining further comprises means for comparing the scanner output for at least one additional repeat length to the comparator threshold during the corresponding time window for each control mark to detect the location of the control mark, and means for discarding those control marks which differ from their stored initial location in excess of a predetermined amount.

24. The control system of claim 23 further comprising means for activating the means for scanning, to obtain a new digital profile map to be further acted upon by the

means for processing and means for determining in response to all control marks being discarded.

25. The control system of claim 21 wherein the means for determining further comprises means for monitoring the difference over successive repeat lengths between the detected location of retained control marks and the respective stored location of each control mark, and for discarding control marks in response to the difference until only a predetermined number of control marks remain.

26. The control system of claim 15 wherein the means for driving the adjusting means further comprises means for inhibiting the driving of the adjusting means in response to a measured difference being less than a predetermined minimum.

27. The control system of claim 15 wherein the means for measuring further comprises means for normalizing the measured difference in location and for displaying the normalized difference.

28. The control system of claim 14 further comprising direction means for automatically determining a primary direction of travel of the web in the web operating apparatus and a secondary direction of travel.

29. The control system of claim 16 further comprising means for allowing the second switching means to energize the adjusting means to advance or retard the web location while in the automatic mode to permit operator intervention.

30. The method system of claim 29 further comprising means for monitoring operator intervention during the automatic mode, and for discarding a control mark and initiating an acquisition of a new control mark in response to operator intervention exceeding a predetermined amount.

31. The control system of claim 14 further comprising means for monitoring the speed of the web operating apparatus and resetting the control system in response to the speed dropping below a predetermined minimum.

32. The control system of claim 14 further comprising means for monitoring the means for detecting and for resetting the control system in response to a failure to detect a control mark for a predetermined time period.

33. Apparatus for automatic control mark acquisition for a control system for maintaining a register condition for successive repeat lengths of a web in a web operating apparatus, comprising:

(a) means for optically scanning the web to produce an output, the output being representative of a longitudinal profile of indicia located on the web surface;

(b) means for sampling the scanning means output and for digitizing the samples to produce digital data;

(c) means for storing the digital data to form a digital profile map of a longitudinal profile of indicia located on the web surface for substantially an entire repeat length;

(d) means for processing the stored digital data to determine the location of indicia contrast changes which conform to predetermined conditions;

(e) means for determining at least one control mark from the located indicia contrast changes and for storing an initial location of each control mark.

34. The apparatus of claim 33 further comprising means for generating a time window of predetermined duration around each control mark initial location.

35. The apparatus of claim 33 wherein the means for processing comprises means for identifying regions of

contrast change and for determining slope values between maximum and minimum detected light levels in the contrast change region, and means for storing the location of at least one contrast change region in response to the slope value exceeding predetermined conditions.

36. The apparatus of claim 35 wherein the means for determining comprises means for identifying contrast change regions adjacent to the located and stored contrast change regions and for discarding any located and stored regions having adjacent regions within a predetermined time window.

37. The apparatus of claim 36 further comprising means for computing a comparator threshold value for each control mark retained, responsive to the minimum and maximum light levels of the contrast change region of each respective control mark.

38. The apparatus of claim 37 wherein the means for determining further comprises means for comparing the scanning means output for at least one subsequent repeat length of the web to the comparator threshold during the corresponding time window for each control mark to detect the location of each control mark and means for discarding control marks which differ from their stored initial location in excess of a predetermined amount.

39. The apparatus of claim 37 wherein the means for determining further comprises means for comparing the scanning means output for a plurality of successive repeat lengths of the web to the comparator threshold during the corresponding time window for each control mark to detect the location of each control mark, and means for monitoring the difference between the detected location of each control mark and the respective stored location of each control mark and for discarding control marks in response to the difference.

40. Apparatus for automatic sensitivity adjustment of a scanner for use in a control system for controlling registration of a web in a web operating apparatus, comprising:

means for scanning the web and digitizing a cross-section of the web to produce a plurality of digital data samples;

means for storing the digital data samples;

means for processing the stored data samples to determine the location of contrast changes which conform to predetermined minimum conditions;

means for determining at least one control mark from the located contrast changes; and

means for automatically determining a sensitivity threshold based upon the magnitude of the contrast change of at least one control mark.

41. The apparatus of claim 40 wherein the means for processing comprises means for identifying regions of contrast change and for determining slope values between maximum and minimum light levels in the contrast change regions, and means for storing the location of at least one contrast change region in response to the slope value exceeding predetermined conditions.

42. The apparatus of claim 41 wherein the means for determining comprises means for identifying contrast change regions adjacent to the located and stored contrast change regions and for discarding any located and stored regions having adjacent regions within a predetermined time window.

43. The apparatus of claim 40 wherein the means for setting a sensitivity threshold comprises means for computing a comparator threshold value for each control

mark retained responsive to the minimum and maximum light level of the contrast change of each respective control mark.

44. A control system for use with an operating apparatus for automatically maintaining a register condition for successive repeat lengths of a sheet substrate having a signature thereon, said control system comprising:

- (a) means for scanning the substrate to detect a reflected light level and to digitize into discrete digital samples the detected reflected light level to produce a scanner output and for storing scanner output digital samples representative of a longitudinal cross-sectional profile of the signature of the substrate for substantially an entire repeat length;
- (b) means for processing at least a portion of the stored scanner output to generate reference control information from the longitudinal cross-sectional profile of the signature;
- (c) means for storing at least a portion of the reference control information to provide stored reference control information;
- (d) means for generating control signals responsive to the relationship between the stored reference control information and at least a portion of the scanner output.

45. The control system of claim 44 wherein the sheet substrate is a web and the operating apparatus is web printing apparatus.

46. The control system of claim 44 wherein the means for generating control signals generates said control signals responsive to the difference between at least a portion of the stored control information and at least a portion of the scanner output and wherein the control system further comprises means for controlling the operating apparatus for selectively advancing and for selecting retarding the successive repeat lengths of the substrate responsive to the control signals.

47. The control system of claim 45 wherein the means for processing comprises means for generating position information associated with the scanner output and means for generating the control information responsive to the scanner output and the position information.

48. The control system of claim 47 wherein the processing means further comprises means for identifying regions of contrast change and to determine slope values between maximum and minimum measured light levels in the contrast change region and means for storing the location of at least one contrast change region in response to the slope value exceeding predetermined conditions.

49. The control system of claim 48 further comprising digital means for storing the scanner output and position information.

50. The control system of claim 49 wherein the means for processing comprises a digital microprocessor.

51. The control system of claim 50 wherein the control information comprises at least a selected portion of the signature representing at least one control mark and position information associated therewith.

52. The control system of claim 50 wherein the means for scanning comprises an optical sensor which produces a scanner output which is an electrical signal representative of at least a portion of the image of the signature.

53. A method of acquiring and maintaining a register condition for successive repeat lengths of a web that is acted on by work applying means of a web operating apparatus which also has adjusting means for adjusting the position of said repeat lengths relative to said work applying means, comprising the steps of:

- (a) scanning the web to produce a scanner output and digitizing the output into a plurality of successive data samples;
- (b) storing the digitized data samples to form a digital map of a cross-section of the web image;
- (c) processing the stored data points to determine the location of contrast changes which conform to predetermined conditions;
- (d) determining a plurality of reference control marks from the located contrast changes and storing the location of each reference control mark;
- (e) detecting the location of each control mark for each successive repeat length;
- (f) measuring the difference between the stored location of at least one of said reference control marks and the detected location of the respective control mark and generating an error signal in response to said difference;
- (g) driving the adjusting means to selectively advance or retard the position of the repeat lengths in response to the error signal.

54. The method of claim 53 wherein the step of determining further comprises measuring the difference between the stored location of each reference control mark and the detected location of the respective control mark for at least one additional repeat length to detect the location of each control mark and discard those reference control marks which differ from their stored location in excess of a predetermined amount.

55. The method of claim 8 wherein the method is repeated starting with the step of storing and digitizing in response to all reference control marks being discarded.
